UNITED STATES PATENT OFFICE.

ALFRED E. GAUDREAU, ALEXANDER J. BEAULIEU, RICHARD J. GAUDREAU, AND CHARLES D. GAUDREAU, OF SPRINGFIELD, MASSACHUSETTS; SAID BEAULIEU ASSIGNOR OF ALL HIS RIGHT TO LEO H. GAUDREAU, OF SPRINGFIELD, MASSACHUSETTS.

CAMP STOOL.

1,408,581.

Specification of Letters Patent.

Patented Mar. 7, 1922.

Application filed May 12, 1921. Serial No. 468,879.

To all whom it may concern:

Be it known that we, ALFRED E. GAUDREAU, ALEXANDER J. BEAULIEU, RICHARD J. GAUDREAU, and CHARLES D. GAUDREAU, all 5 citizens of the United States of America, residing at Springfield, in the county of Hampden and Commonwealth of Massachusetts, have invented certain new and useful Improvements in Camp Stools, of which 10 the following is a specification.

This invention relates to improvements in camp stools of the type in which a circular rod or tube is provided for supporting the foldable leg members, and also for attaching 15 the foldable arms or brace members which support the canvas seat proper.

An object of the invention is to provide a camp stool that can be readily folded into a compact volume for transportation or 20 when not in use.

A further object is to provide a camp stool having means for readily detaching the seat portion which is usually made of canvas for the purpose of rolling it around the 25 foldable parts of the stool, thus using it as an envelope or protecting cover.

A further object is to provide a platform member which is designed to receive the lower ends of the foldable legs, whereby the 30 stool may be used to support the user in places where the lower ends of the legs might sink into the soil.

A further object is to provide means for firmly locking the legs when placed in an 35 extended position for use.

Referring to the drawings:

Fig. 1 is an elevation view showing the stool in extended position and ready for use, the legs being locked, and the lower ends of 40 the same engaging the platform member.

Fig. 2 is an enlarged sectional view taken in a plane through the axis of the center post and showing two of the legs extended, the brace members for the legs, and the runner 45 construction for the foldable braces which support the canvas seat member.

Figs. 3 and 4 are detail views, each showing a different device for attaching the canvas seat to the outer ends of the supporting braces.

Fig. 5 is a transverse sectional view on the line 5—5 of Fig. 4.

Fig. 6 is a detail view showing one corner of the canvas seat with one of the fold-

able members attached thereto which engages the upper and outer ends of the foldable seat supporting braces.

Fig. 7 is a modification of the devices for attaching the seat proper to the foldable seat supporting braces.

Fig. 7^A is a further modification of the seat attaching devices.

Fig. 8 is a detail view showing one of the foldable foot pieces at the lower end of the leg members, and also the means for attaching the footpiece to the foldable supporting platform.

Fig. 9 is a plan view of the foldable platform for receiving the lower ends of the foot pieces.

Fig. 10 is a partial top plan view of the upper end of Fig. 2.

Fig. 11 is a horizontal sectional view on the line 11—11 of Fig. 2, showing the spring engaging the kerf for retaining the leg locking bolt in its lowered or operative position.

Fig. 12, is an end view of the stool with the legs and seat supporting braces folded inward against the tubular post.

Fig. 13 is a sectional view on the line 13—13 of Fig. 2 illustrating a portion of the braces for the legs in their locked position and the slideable locking bolt engaging the braces.

Fig. 14 is a sectional view on the line 14—14 of Fig. 12 showing one of the seat supporting braces and one leg in section, also the tubular post, and the slideable leg locking bolt for the braces.

Referring to the drawings in detail: 1 designates the supporting post member 90 which as shown is preferably tubular, as indicated in Fig. 2. Attached to the lower end of the tubular member 1 is a collar 2 having the bracket arms 3. Pivotally attached to these arms are the leg members 4 which are preferably formed of channel or U-shaped metal, as indicated in section in Figs. 11 and 12. These are pivotally connected to the brackets 3 by means of the pins 5. 6 designates foldable foot pieces that are pivotally attached to the lower ends of the leg members 4. These pieces, as shown in Fig. 12, are U-shaped and are for the purpose of engaging and resting on the platform 7, shown in Fig. 9. This platform is preferably made in two pieces of metal which are pivoted together at 8.

Fig. 5 is a transverse sectional view on the line 5—5 of Fig. 4. Fig. 6 is a detail view showing one corner of the canvas seat with one of the fold-

indicates the upturned edges of the platform 7 at each of the corners, and having the lip portion 10 for receiving the foot pieces 6, as shown in Fig. 8. The object of this platform 5 form is to prevent the lower ends of the legs from settling into the ground in case it is soft. For the purpose of retaining the legs in the operative position shown in Fig. 1 the braces or cross members 11 and 12 10 are provided. These are pivotally connected to two of the legs 4, as indicated at 13, one of the pivots being shown in Fig. 2. The opposite end of each of these braces is formed with a hook portion 14 which engages 15 a pin 15 on the oppositely located leg. These braces are notched as shown in Fig. 2, so that when they are in this position they form a lock. In order to retain the braces in the operative position the slidable 20 bolt 16 is located in the tubular member 1. This bolt is formed with the cross grooves 20 at its lower end for receiving and resting on the upper edges of the braces 11 and 12, as shown in Fig. 13, whereby the legs are 25 prevented from having a twist or turning movement, and assists in making the stool a rigid structure. For the purpose of retaining the sliding bolt 16 in its lowered position a kerf or groove 17 is cut or formed 30 therein for receiving the spring 18, which is attached to the collar 2, as shown. A kerf 19 is also cut near the lower end of the rod 16 for retaining the bolt in an elevated position, as indicated in Fig. 14, when the parts 35 of the stool are folded. The cross grooves are indicated by the numeral 20 in the lower end of the slidable rod 16.

Rotatably located in the upper end of the tube 1 is a collar 21 which engages the 40 shoulder portion 22 and rotates thereon. Attached to this collar are the seat supporting braces 23 by means of the pivot pins 24. Located immediately below the shoulder portion 22 is a slidable collar 25 which also 45 rotates on the post 1. Attached to this collar are the links 26 by means of the pivot pins 27. These links are attached to the seat supporting braces 23 and to the collar 25 shown in Fig. 1. Attached to the outer ends of 50 the braces 23 is the seat member 29 which is preferably formed of canvas material. The seat is formed at its corners with the reinforcing metal plates 30 that are bent around the edge of the canvas and riveted 55 thereto, as indicated at 31. Pivotally connected to the plates 30 at the points 29' are the foldable extension pieces 32, each of which are formed with a longitudinal slot indicated at 33 to receive the upper ends of 60 the braces 23, as shown in Fig. 1, whereby the seat member may be readily attached to and removed from these braces. Since the pieces 32 are pivotally attached to the seat 65 29 they may be folded into the dotted line position shown in Fig. 6, to permit the

canvas to readily fold. These extension pieces permit the seat to be folded into small compass when removed from the braces 23.

Figs. 4 and 5 show a modification of the attaching means between the seat 29 and the braces 23, which comprises a tubular member 34 which slips over the arm 23, as shown in Fig. 5. A pin 35 limits the inward movement of the pieces 36.

Fig. 7 is a further modification of the attaching means between the seat 29 and the brace members 23. It comprises slots 37 and 38 for receiving the pins 39 and 40, whereby the pins are locked in position when weight is applied to the seat portion, and will at the same time permit the seat to be readily removed from the brace members.

The apparatus is folded as follows: By withdrawing the spring 18 and raising the bolt 16 into the position shown in Fig. 14 85 the leg braces 11 and 12 are then folded into the position shown in this figure. After removing the seat 29 the collar 25 is moved down the rod 1, as shown in Fig. 14 carrying the braces 23 and links 26 with it. The 90 folded position of the parts is shown in Figs. 12 and 14 in end and sectional view, and these may be wrapped with the canvas seat 29.

It will therefore be seen that I have provided a foldable camp stool which can readily be opened or closed, and one that occupies a small compass, making it easily stored or carried. It is also very strong and rigid when in use, especially when the platform 7 100 is employed to support the same.

Referring to Fig. 7A; 41 designates a piece that is pivotally connected to the bent, offset or crank part 42 of the wire insert piece 43 that is inserted in the corner part of the 105 canvas seat 29. This view shows the wire insert piece in section, with the piece 41 engaging the underside of the seat. It is to be understood that the piece 41 is formed with a slotted end 32 to receive the end of the 100 brace 23.

When the part 41 is removed from the support 23 it may be turned on the crank or offset part 42 and rolled up with the canvas seat.

What we claim is:

1. A camp stool, having in combination with a center post member, leg members pivotally attached thereto, means for retaining the leg members in an extended and locked position, said means including crossed braces having locking engagement with each other midway of their lengths, means including a recessed bolt for locking the braces in their operative position, a seat connected to the center post member, and means including extension pieces on the seat connecting means for detachably securing the seat to said member.

2. In a foldable camp stool, a center post,

- legs pivotally attached thereto, means for locking the legs in their operative position, said means including braces pivoted to one leg and engaging an oppositely located leg 5 member, said braces crossing each other and having locking engagement, a bolt slidably mounted in the center post member and formed with grooves to engage the brace members at their crossing points.
- 10 3. In a foldable seat structure, the combination with a tubular member, legs pivotally attached at one end, means for retaining the legs in their operative or open position, a slidable bolt for locking the leg retaining 15 means, a lock for the bolt, comprising a kerf therein and a spring engaging the kerf for holding the bolt in either its operative or inoperative positions, as described, a seat attached to the opposite end of the tubular 20 member, braces and links for supporting the seat and for permitting the same to rotate about the post member.
4. In a foldable seat structure the combination with a post member, legs pivotally 25 connected thereto for folding into a supporting or open position, or against the post in their closed position, a seat member, braces and links connected together and rotatable about the post for supporting the 30 seat, the links being slidable on the post to permit the braces to move either into their seat supporting position or against the post, as described, said seat member being detachably connected to the braces.
- 35 5. A foldable seat structure having in combination, a center post, legs pivotally connected thereto, means for locking the legs in an open or inclined position and including a bolt slidably mounted with relation 40 to the post, and braces for the legs with which the bolt engages.
6. In a camp stool, a center post, legs pivotally connected thereto, means for retaining
- the legs in their supporting position, said means including crossed braces pivotally 45 connected to some of the legs and engaging pins on the opposite legs, one of said braces having a notch to engage the other brace, and a member formed with grooves to engage the braces at their crossing points. 50
7. In a foldable camp stool, the combination with a center post, of leg supporting members pivotally connected thereto, braces engaging the supporting members, means for retaining the members in their open position, including a sliding bolt mounted in the post and having crossed recesses in its lower end for engaging the braces, and means for retaining the bolt in either its operative or inoperative position, as described. 55
8. A foldable seat construction having in combination, a center post, two rotatable collars thereon, braces and links connected together and to the collars, one of the collars being slidable on the post, legs connected 60 to the post, a seat, extension pieces on the seat and formed with slots to removably engage the upper ends of the braces whereby the seat may be removed and the legs, braces, and links folded into a small compass, as described. 70
9. In a foldable seat structure, the combination, of a device secured to the canvas seat member and comprising a member having arm portions designed to be secured to the 75 folded edge of the canvas, a crank or offset portion in the device, a member having a slot at one end and an eye to receive the crank or offset portion to permit the member to be folded into close and parallel relation 80 to the canvas seat member for the purpose described.
